UNITED STATES PATENT OFFICE.

CHARLES L. GINTY, OF LOCKPORT, NEW YORK.

INTERNAL-COMBUSTION MOTOR.

Application filed January 19, 1923. Serial No. 613,672.

To all whom it may concern:

Be it known that I, CHARLES L. GINTY, a citizen of the United States of America, and resident of Lockport, county of Niagara, 5 State of New York, have invented certain new and useful Improvements in and Relating to Internal-Combustion Motors, of which the following is a specification.

This invention relates to certain improvements in internal combustion motors; and the nature and objects of the invention will be readily recognized and understood by those skilled in the arts involved in the light of the following explanation and detailed 15 description of the accompanying drawings illustrating what I at present consider to be the preferred embodiments or mechanical expressions of the invention from among various other forms, arrangements, combinations 20 and constructions of which the invention is capable within the spirit and scope thereof.

The invention and the various features thereof while adapted to internal combustion motors generally, are more particularly directed and applicable to those types of internal combustion motors known as "oil-burning" motors. These so-called "oil-burning" motors are characterized generally 30 by the injection or induction of liquid fuel directly into the motor together with the proper quantities or proportions of air, the liquid fuel being preferably atomized in any suitable manner; and the burning of 35 the liquid fuel by highly compressing the air charge in the motor to raise the temperature to a point where the liquid fuel is ignited.

In one form of the so-called "oil-burning" 40 types of internal combustion motors in general use and well known and understood by those skilled in this art, liquid fuel and air are admitted to a confined space or chamber in communication with the combustion or 45 compression space of the motor and the more volatile hydro-carbons through the action of the heat of the walls of this confined chamber are vaporized and mix with the air admitted to form a readily combustible preliminary charge within the confined chamber. Upon compression of the main air charge in the combustion or compression chamber of the motor to the proper point, 50 the heat created thereby ignites the preliminary charge in the confined chamber with

the result that the main liquid fuel charge is forcibly ejected from the confined chamber and discharged into the compression or combustion space of the motor in an atomized and ignited or burning state where 60 further combustion takes place and power is developed in the motor in the usual manner.

In the operation and use of "oil-burning" 65 motors involving the principles of operation above briefly outlined, complete atomization of the main liquid fuel charge is not always obtained, particularly during the operation of cranking a motor preparatory to starting the same, so that frequently what may be 70 aptly termed or referred to as "solid" fuel is admitted to the combustion or compression space of the motor with the resulting disadvantages, such as increased carbon deposits in the motor and the serious interference with proper lubrication of the motor, 75 as will be readily understood by those familiar with the internal combustion motor art. Therefore, one of the main objects, 80 from among others, of the present invention is the practical elimination of the disadvantages above referred to by providing for the vaporization of any "solid" fuel resulting 85 from incomplete atomization of the liquid fuel admitted or drawn from the confined space or chamber into the compression space of the motor, and to thus materially reduce admission of "solid" fuel into the motor.

With internal combustion motors of the 90 type in which the fuel is ignited by compressing a charge thereof in the motor to raise the temperature to the point where ignition of the charge takes place, as in the form of this type above referred to, the time 95 of ignition depends primarily upon the point where the compression is sufficient to result in a temperature to cause combustion, and it is a further object of this invention to provide for the varying of the point in the 100 cycle of the motor where ignition takes place by varying the point at which the compression results in a temperature to cause ignition of the charge.

A further object of the invention is to 105 lower or reduce the degree of temperature or ignition point of the fuel charge by more completely atomizing and vaporizing the liquid fuel so as to correspondingly reduce the compression required to attain such tem- 110

perature, with a resulting decrease in the power required to force a motor piston to compress the charge to the required point; and a further object is to so form, arrange and construct a motor of the type referred to, as to provide for a more rapid rise in compression and resulting rise in temperature to the required degree at the latter end of the compression stroke of a piston, to thereby materially lower or reduce the force acting against a piston on the compression stroke thereof.

20 A further object of the invention is to provide for the preheating of the main air charge before induction into a cylinder by utilizing the heat created in a muffler or other portion of the motor exhaust line, as well as by utilizing the heat of a cylinder wall.

20 A further object of the invention is to provide means for preheating a motor cylinder and associated structure preliminary to starting.

With the foregoing and various other objects in view, which other objects will be readily recognized and appreciated by those skilled in the art from the following description and explanation, the invention consists in certain novel features in construction and in arrangements and combinations of elements, as will be more fully and particularly set forth and specified hereinafter.

Referring to the accompanying drawings:

Fig. 1, is a fragmentary view in end elevation taken from the cylinder head end of a horizontal single cylinder internal combustion motor of the "oil-burning" type embodying the various features of the invention.

Fig. 2, is a vertical, longitudinal section taken along the line 2—2, of Fig. 1.

Fig. 3, is a vertical longitudinal section through the diametrical center and taken on the line 3—3, of Fig. 1.

Fig. 4, is a view in end elevation of the inner wall or face of the cylinder head of a motor embodying features of the invention.

50 Fig. 5, is a detail section taken on the line 5—5 of Fig. 2, showing the intake valve stem mounting and air intake passages.

An internal combustion motor of the "oil-burning" type embodying the various features of the invention is illustrated in the accompanying drawings by way of an example of one physical expression or mechanical adaptation of which the invention is capable, and to permit of an explanation of the principles of the invention and their applied results and advantages to enable those skilled in the art to understand the same. It will be clear that the various features of the invention are applicable to other types and forms of internal combustion mo-

tors and it is not intended to limit the invention to application to the illustrated type of motor or to the mechanical expressions which the principles of the invention have taken in the illustrated application thereof, 70 the type of motor disclosed having been selected because the problems solved and the disadvantages overcome by the invention are encountered in an accentuated state therein, and hence the invention and various 75 features thereof can be more sharply and clearly brought out and explained.

The illustrated type of "oil-burning" internal combustion motor is well known and understood in this art, and comprises, in the present instance, a horizontal type cylinder 10 having the usual cooling jacket 11 and cooling liquid supply tank 12 mounted in communication therewith. A piston 14 is mounted in the cylinder 10 and a removable head 15 is mounted on and closing the cylinder in the usual or any other desired manner. The cylinder head 15 is provided with cooling liquid circulation chamber 16 in communication with the space formed by the cylinder jacket 11. The lower portion of the inner wall of the cylinder head 15 is formed to provide a block 17 which projects a distance inwardly into the cylinder 10 beyond the plane of the upper portion 18 of the cylinder head. The projecting block 17 terminates within the cylinder 10 in a plane spaced from the piston 14 when at the limit of its stroke, so that a combustion or compression chamber 19 is formed in the cylinder. An intake port 20 and an exhaust port (not shown) are provided extending through the projecting block 17 forming the lower portion of the inner wall of the cylinder head, and these ports are respectively 105 in communication with the tubes 21 and 22 extending through and across the cooling liquid space 16 in the cylinder head and forming communicating passages for the 110 said ports, respectively.

Valve seats are provided in the intake and exhaust ports at points spaced outwardly therein from the inner face of the projecting block 17, the valve seat 23 i.e. the intake port being shown in Fig. 2 of the drawings. 115 An exhaust valve 24 is mounted in and controlling the exhaust port through the medium of a valve operating stem 25 extending through the tube 22 and outwardly a distance beyond the cylinder head in the usual manner. An intake valve 26 is mounted in the intake port 20 and adapted to seat on the valve seat 23 thereof. The intake valve 26 is provided with the usual operating stem 27 which can be operated in 120 any suitable manner, as for example of the suction operated type having the coil spring 28 maintaining the valve normally seated and closing the intake port 20.

According to the illustrated embodiment 130

of intake valve mounting of the invention, the valve stem 27 is slidably mounted in the sleeve 29 secured in the outer end wall of the cylinder head 15 and extending inwardly a distance into the valve stem housing or tube 21. The portion of the sleeve 29 extending within the tube 21 is formed of a flat sided exterior shape or contour, such for example as octagon shape as shown, and thus forms a series of longitudinally extending air passages 30 around the sleeve 29 (see particularly Fig. 5 of the drawings) in communication at their inner ends with the space or passage around and between the tube 21 and the stem 27, which latter is of smaller diameter than the interior of the tube, as will be clear by reference to Fig. 2 of the drawings. A circumferential groove or annular depression 31 is formed around the outer end of the sleeve 29 in communication with the series of air passages 30. A main air intake passage 32 is provided in the outer wall of the cylinder head 15, in communication at its inner end with the groove 31, and extending radially or laterally from the tube 21 through the outer wall of the cylinder head 15 to one side thereof. Thus, air is drawn into the cylinder 10 through intake port 20, tube 21, passages 30 and groove 31, and the air intake passage 32 in the outer wall of the cylinder head.

The exhaust port is in communication with the inner end of a passage formed in the tube 22 around the valve stem 25, and the outer end of this passage so formed in the tube 22 is in communication with an exhaust chamber 33 provided in the cylinder head 15 and extending radially or laterally from the tube 22. The exhaust chamber 33 extends to and discharges through an exhaust pipe 34 at the same side of the cylinder head to which the main air intake passage 32 extends. (See Fig. 1 of the drawings.) Any suitable muffler 35 is connected with the exhaust pipe 34 from the chamber 33 and receives the motor exhaust gases therefrom.

Thus, the motor exhaust gases discharge through the exhaust port in the cylinder head, tube 22, chamber 33 in the cylinder head, pipe 34, and the muffler 35 to atmosphere.

A fuel inlet passage 36 is formed above the valves 24 and 25, in communication at its inner end with the compression or combustion space 19 at the head of the cylinder 10, and extending a distance through the cylinder head. At the outer end of the passage 36 a cup 37 is mounted on the lower end of a suitable plug 38 and projects into the passage 36. The amount of fuel is controlled by a needle valve 39, and the time of fuel delivery and the admission of a small quantity of air is controlled by the puppet valve 40. The foregoing arrangement and

the operation thereof is in general use and well known to and understood by those skilled in this art, and hence it is not deemed necessary herein to present a detailed description and explanation thereof. It is sufficient to state that the fuel charge is supplied through the above arrangement and atomization and ignition of the liquid fuel charge is effected by compression created temperature in the cup 37, passage 36 and the compression space 19 of the cylinder 10.

The fuel passage 36 discharges through the upper portion of the cylinder head 15 above the projecting block 17 thereof. The air intake port 20 is provided with an annular groove 41 therein and therearound between the intake valve 26 and the compression space 19 of the cylinder. A passage 42 extends upwardly through the projecting block 17 of the cylinder head and opens through the upper edge thereof in communication with the fuel passage 36, so that the air inlet port 20 is in communication with the fuel inlet passage 36, through the projecting block 17 therebetween.

In these so-called "oil-burning" types of internal combustion motors where ignition is effected by heat created from highly compressing the charge in the cylinder, it follows that the time of ignition is dependent upon the point in the compression stroke of the motor at which the necessary compression is attained. Now, the present invention provides what is in effect a timing device for such motors, so that the time of ignition and firing of the explosive charge can be readily varied and adjusted. This feature of the invention provides means for varying or changing the capacity of the combustion or compression space of a motor cylinder with a resulting change in the point at which the required ignition compression is reached. The illustrated mechanical adaptation of this feature comprises a cylinder 43 formed in the upper portion of the cylinder head 15 and open at its inner end to the compression space 19 of the cylinder 10, above the projecting block 17 of the cylinder head. The outer end of the cylinder 43 is closed by a suitable plug 44. A piston 45 having the usual compression rings 46 is mounted for reciprocation in the cylinder 43, by means of a screw 47 and exterior operating handle or wheel 48. By advancing the piston 45 into the compression space 19 of the cylinder 10 the capacity thereof can be reduced, thus advancing the time of firing by causing the compression to more quickly create a firing or ignition temperature, while by retracting or withdrawing the piston 45 into the cylinder 43 the capacity of the compression space in the cylinder 10 can be increased so as to retard the firing or ignition point, as will be clear to and readily

understood by one familiar with this type of internal combustion motor.

The operation of a motor embodying the hereinbefore described principles and features of the present invention will now be described. Assuming that the motor employs the four stroke cycle, then upon completion of the exhaust stroke the exhaust valve is closed and as the piston 14 moves 10 in the cylinder 10 away from the head 15 the intake valve 26 opens and pure air is drawn into the cylinder 10. Upon opening of the intake valve 26, or shortly thereafter, the valve 40 is opened, through the medium 15 of any of the well known mechanisms for this purpose (not shown) and oil is supplied to the cup 37. Simultaneously with the delivery of the fuel oil to the cup 37, which forms the vaporizer or atomizer for 20 the fuel, a small quantity of air is drawn into the cup 37 and this air, aided by the heat of the cup 37, causes vaporization of the more volatile constituents of the oil charge in the cup. This carbureted air thus 25 formed during the suction stroke of the piston will be confined in the cup 37 during the compression stroke due to the restricted openings 49 by which the cup is placed in communication with the fuel passage 36 30 and compression space 19.

After the piston completes the suction stroke it starts toward the cylinder head on the compression stroke with both intake and exhaust valves closed. Thus, toward the end 35 of the compression stroke the main air charge in the cylinder and in the fuel passage 36 has been highly compressed with the temperature raised to a sufficient degree to ignite the carbureted air charge or explosive charge in the cup 37. The preliminary explosion of the carbureted air then takes place in the cup 37 and the main fuel charge is forcibly ejected from the cup through the openings 49, which ejection 40 thoroughly atomizes the main fuel charge for mixture and burning with the main air charge in the combustion or compression space 19 of the cylinder 10. The power stroke then results from the burning of the 45 atomized fuel charge with the main air charge, which is followed by the exhaust stroke and the cycle of operations is repeated in the usual manner.

In the operation of starting an internal 50 combustion motor of the referred to type, the usual cylinder compression release (not shown) is opened and the fuel control or supply valve 40 is also opened to admit fuel to the fuel cup. The motor fly wheel (not 55 shown) is rapidly turned several revolutions and the compression release (not shown) is immediately closed. The momentum of the fly wheel will turn the motor against the compression, igniting the fuel in the cylinder and causing the motor to start. How-

ever, during the foregoing operations it is found that through the suction of the motor piston solid fuel is frequently drawn from the fuel cup and admitted to the cylinder. With the invention, the direct admittance 70 of solid fuel in the foregoing manner is materially reduced and practically eliminated, as any such liquid fuel will drain or pass from the fuel passage 42 in the projecting block 17 of the cylinder head and be trapped 75 and collect in the groove or depression 41 in the intake port 20. The main air charge drawn into the cylinder through the intake port 20 passes over, and with the aid of the retained heat in the cylinder head block 17, 80 vaporizes and mixes with the liquid fuel collected in the groove 21, so that the "solid" liquid fuel is drawn into the cylinder in a vaporized condition. Further, during the operation of the motor, complete atomization 85 and burning of the liquid fuel ejected from the cup 37 through the fuel passage 36 does not always take place, with the result that solid fuel may collect in the passage 36 and drain into the cylinder 10. In the event of 90 the foregoing conditions, any solid fuel which enters the passage 36 will drain through the passage 42 and collect in the groove or depression 41 in the intake port 20. Thus, with a motor embodying the foregoing features of the invention, the entrance 95 of liquid fuel in the "solid" state is materially reduced.

Due to the form of the cylinder head with its projecting block 17, upon the latter end 100 of the compression stroke the main charge has an upward movement, part thereof passing upwardly through the passage 42, and this movement has a tendency to further and more thoroughly vaporize and mix the 105 same. With a more highly vaporized mixture the temperature at which it may be ignited is lowered, so that the degree of compression to attain the required temperature is lowered. Therefore, with a lower degree 110 of compression the force acting against the piston on the compression stroke is decreased with a corresponding increase in power. Also with the form of cylinder head of the invention and the resulting shape of the compression space, on the compression stroke 115 the compression rises quickly at the latter end of the stroke and hence the distance which the piston has to travel against high compression is lessened and an increase in 120 power is secured.

The invention includes and embodies means for preheating the main air charge before delivery into the motor, and means for preheating a motor cylinder and associated structure preliminary to starting the motor when cold. In Fig. 1 of the accompanying drawings a muffler 35, of any desired or suitable type, is shown connected in communication with the exhaust pipe 34 and 130

receiving exhaust gases from the motor cylinder 10. The muffler 35 is provided with a jacket 50 spaced therefrom and forming an air space 51 around the muffler 35. The intake passage 32 to the intake port 20 is connected and placed in communication with the air space 51 between the muffler 35 and jacket 50, through the medium of a conduit 52. An enlarged bore forming a socket 53 is provided in the outer wall of the cylinder head 15 surrounding and in communication with the open intake end of the passage 32. One end of the conduit 52 is provided with a flange 54 surrounding the same. The flanged end of the conduit 52 is fitted into the socket 53 and coil springs 55 are interposed between the inner wall of the socket 53 and the conduit flange 54. A retaining plate 56 is placed over and around the conduit 52 and removably secured to the wall of the cylinder head adjacent thereto. In this manner the conduit 52 is loosely confined in the socket 53 in communication with the main air inlet passage 32. The outer end of the conduit 52 extends into the air space 51, around the muffler 35 and a port or opening is provided in the conduit 52, which opening is controlled by a closure or door 57. By the foregoing arrangement heated air is drawn by the motor from the space 51 around the muffler 35 through conduit 52 and the air passage 32 in communication therewith. The door 57 provides for varying the temperature of the air admitted to the motor by permitting the entry of cold air directly into the conduit.

In cold weather motors of the type illustrated are difficult to start and means is provided by the invention for warming the cylinder 10 and the intake and exhaust passages preliminary to starting a motor. A fire-box or heater 60 is mounted on the interior of the muffler and is provided with an igniting and draft opening 61 through a wall of the muffler to permit of lighting fuel in the fire-box from the exterior of the muffler. The fire-box or heater 60 has a cover 62 pivotally mounted therein for controlling the burning of the fuel therein. The cover 50 is controlled from the exterior of the muffler by means of a handle 63 and is maintained in desired adjusted position by a flat spring element 64 which engages the free edge of the cover. A guide or baffle plate 65 is provided in the muffler and extends to the exhaust chamber or space 33 in the cylinder head 15. In operation, fuel is ignited and burned in the fire-box 60 and the air in the muffler is heated thereby. With the exhaust valve open the heated air passes upwardly through the exhaust chamber 33 and into the cylinder 10 through the exhaust port, and the cold air in the cylinder passes out through the lower side of the exhaust port and chamber 32, the cold air being

guided by the baffle plate to the fire-box. Thus, a circulation of air is set up and the cylinder 10 is brought up to the required temperature. During operation of the fire-box or heater 60, the air in space 51 would 70 be warmed and pass into the main air inlet 32, warming the same. In the foregoing manner the temperature of the cylinder can be raised to facilitate starting of the motor.

It is evident that various changes, modifications, variations and substitutions might be resorted to without departing from the spirit and scope of the invention and hence I do not wish to limit the invention to the exact disclosures hereof.

Desiring to protect my invention in the broadest manner legally possible, what I claim is:

1. In an oil burning motor, a cylinder head having an inwardly projecting block 85 forming the lower portion of the inner wall thereof, intake and exhaust ports formed through said block, a fuel passage opening and discharging through the inner wall of the cylinder head above said projecting block, and the said block formed with a passage extending therethrough from said fuel inlet passage to and discharging into said intake port.

2. In an oil burning motor, a cylinder head, a fuel passage opening and discharging through the inner wall thereof, an intake port in said cylinder head below said fuel passage, and a passage extending from said fuel passage through said cylinder head to 100 and discharging into said intake port.

3. In an oil burning motor, a cylinder head, a fuel port therein, an air intake port therein, and a fuel vaporizing passage formed in the cylinder head extending between and in communication with said fuel port and said air intake port.

4. In an oil burning motor, a fuel inlet port, an air intake port spaced and separate from said fuel inlet port, and a communicating passage extending from said fuel inlet port to and discharging into said air intake port whereby unvaporized fuel from said fuel inlet port drains therethrough to said air intake port.

5. In an oil burning motor, a cylinder head, a fuel inlet passage therethrough, an air intake passage therethrough, a valve mounted in said air intake passage spaced inwardly from the discharge end thereof, 120 and a passage extending from said fuel inlet passage to and discharging into said air intake passage between the discharge end thereof and said valve.

6. In an oil burning motor, a cylinder 125 head, an inwardly projecting block thereon, a fuel port in said head and discharging adjacent said block, an air intake passage extending through said block, and a passage formed in said block and extending 130

therethrough from said air intake passage to and opening through the wall of said block adjacent said fuel inlet port.

7. In an oil burning motor, a cylinder head having a portion of the inner wall thereof formed by an inwardly projecting block, a fuel inlet port in the inner wall of the cylinder head adjacent the inner edge wall of said block, an air intake passage formed in the cylinder head through said block, a fuel collecting depression formed in said air intake passage at the discharge end thereof, and the said projecting block provided with a passage extending there-through from the inner edge wall adjacent said fuel inlet port to and in communication with the fuel collecting depression of said air intake passage.

8. In an oil burning motor, in combination, a fuel inlet port, an air intake port in communication through a passage with the fuel inlet port to receive unvaporized fuel therefrom, means for heating air by the motor exhaust in communication with said air intake port and discharging heated air therethrough and means for preheating the motor through said air intake port preparatory to starting the motor.

9. In an oil burning motor, in combination, an air intake port, an exhaust port in communication with and discharging into an exhaust muffler, a fuel inlet port in communication through a passage with said air intake port for discharging unvaporized fuel thereinto, means in communication

with said air intake port and discharging heated air therethrough, and means mounted in operative relation with said muffler for preheating the motor through said air intake and exhaust ports.

10. In an oil burning motor, a fuel inlet port, an independent air intake port, means for discharging surplus unvaporized fuel from said fuel port to said air intake port for vaporization, and means for heating air before discharge through said air intake port.

11. In an oil burning motor, separate fuel inlet and air intake ports, an exhaust port, means for discharging surplus unvaporized fuel from said fuel inlet to said air intake for vaporization thereof, and means in communication with said exhaust port for heating air by the exhaust gases before discharge through the said air intake port.

12. In an oil burning motor, a cylinder, a head therefor formed with a portion of the inner wall projected a distance into the cylinder to form a cham in the head, the said head having a fuel inlet therethrough discharging into the chamber so formed and an exhaust port and an air intake port in said projected portion, and valves mounted in the air intake and exhaust ports in the projected portion and disposed in substantially the plane of the remaining portion of the inner wall of said head.

Signed at Lockport, New York, this 22d day of November, 1922.

CHARLES L. GINTY.
